MODULATION INDICATOR

Lester B. Holmes, Paterson, N. J.

Application May 24, 1938, Serial No. 209,846

4 Claims. (Cl. 179—171.5)

This invention relates to electrical indicators generally. More particularly this invention relates to a method and apparatus for indicating modulation in apparatus such as radio telephone transmitters and the like.

An object of this invention is to provide an indicating tube of elongated shape in which different sections of the tube are coated with different types of fluorescent materials to produce different color indications depending upon the extent to which the tube is energized.

Another object of this invention is to provide a modulation indicator for radio telephone transmitters, said modulation indicator employing a tube with a fluorescent screen which is adapted to act as an inexpensive and reliable visual modulation indicator.

A further object of this invention is to provide an electrically energized indicating tube of elongated shape in which different sections of the tube are coated with different types of fluorescent materials to produce different color indications, said fluorescent materials being so arranged that the tube when energized by a speech or otherwise modulated or varied electric current will give different indications depending upon the intensity, loudness or volume of the speech or other modulating or varying energy.

Another object is to provide an electrical indicator comprising a tube with a plurality of screens of fluorescent material, different ones of said screens being excited and caused to become luminescent when different sound energy or other energy levels are to be indicated.

Still another of this invention is to provide a modulation indicator employing a tube made of transparent or translucent materials, the inside of said tube being coated with particles of fluorescent and/or phosphorescent material; said tube being connected to a radio transmitter so that different ones of said particles are caused to become luminescent depending upon the extent or degree to which the signal of the radio transmitter is modulated.

Other and further objects will be apparent to those skilled in the art to which this invention relates from the following specification and the claims.

In accordance with this invention I provide a simple and efficient indicator which may be made relatively accurate and without great expense. One of the uses of the indicator of my invention is to indicate when the radio signal emitted by a radio telephone transmitter is modulated over 100%. However, it will be obvious that this in-

dicator may be calibrated to indicate various percentages of modulation and of course my invention is not to be limited to an indicator adapted for the 100% indication only. My indicator consists primarily of an elongated glass tube which is provided with an electrode at one end connected by means of a small condenser to one of the high frequency circuits of the radio transmitter. The inside of this glass tube is coated with fluorescent materials by sucking solutions containing such materials up into the tube to the desired height. When the solutions are emptied from the tube by cutting off the suction a coating of the desired material remains on the inside wall of the tube. The air is exhausted from the tube and inert gas or a mixture of inert gases placed therein to facilitate electrical bombardment of the fluorescent screen through ionization of the inert gases. This ionization does not have to be visible and the pressure of the inert gases in the tube should be relatively low when compared to atmospheric pressures. A small quantity of mercury may be placed inside of the tube to produce a brighter fluorescence of the screen material of the tube. The ultra violet rays produced through the action of the mercury vapor in the tube also excite the screen and assist the bombardment action in causing the screen to become fluorescent. The top of the tube, that is the end opposite the end provided with the electrode, is provided with a small cap which is connected to the metal chassis of the radio transmitter of low power. This connection may not be necessary where the indicator is used with transmitters of relatively high power.

After the indicator is connected to the transmitter as outlined above the small coupling condenser is adjusted so that the tube indicates at the "no-modulation point." This is when the transmitter is not being modulated and only the un-modulated carrier wave is being transmitted. When this adjustment for no-modulation is obtained the indicator is set to indicate when the signal of the transmitter is modulated over 100%, inasmuch as modulation over 100% will cause the uppermost portion of the fluorescent screen, which has color characteristics materially different from those of the screen in the lower portion of the tube, to be excited. Thus by adjusting coupling condenser of the indicator at the "no-modulation point" when the transmitter is not modulated, the indicator will reliably show when the 100% modulation point is reached and/or exceeded.

Various other uses suggest themselves for the

multiple fluorescent screen indicator of my invention. Among these various uses is that of indicating the sound intensity of a person speaking or singing into the microphone of a radio broadcasting station, public address system or any telephone circuit. The indicator tube of my invention is easily applied to this use simply by connecting suitable electrodes in the tube to the output circuit of an amplifier so that some of the voice modulated currents developed in the microphone are amplified and impressed upon the indicator tube.

Further details of this invention may be obtained from the following specification and the drawings in which, briefly, Fig. 1 illustrates the indicator of my invention and a diagram of connections employed therewith; Fig. 2 is a cross section of the tube taken along the lines of 2-2 of Fig. 1; Fig. 3 is a cross section of the tube taken along the lines of 3-3 of Fig. 1; Fig. 4 illustrates another embodiment of this invention and Fig. 5 is a schematic diagram showing still another arrangement of this invention.

Referring to the drawings more particularly, reference numeral 10 designates an elongated tube made of transparent material, such as glass, "Bakelite," fused quartz, "Pyrex" and the like. An electrode 11 made of material, such as, nickel, tungsten, graphite, or the like, is supported by the wire 12 which is fused into one end of the tube and projects through the glass material to contact the cap 13 of brass or similar material positioned on the outside of the glass tube. This contact 13 is connected at 14 to the wire 15 and the variable condenser 16. The other end of the tube 10 is provided with a cap 17 of metallic material. This cap 17 is not connected to the inside of the glass tube by any metallic connection. However when the potential is applied to this cap with respect to the electrode 11 an electrostatic field is set up between this cap and the aforesaid electrode which is desirable in the operation of the device.

The condenser 16 is connected by the wire 22 and a variable top 22a to the tank coil 23 of the high frequency power amplifier tube 24 of the radio transmitter 25. This power amplifier 24 amplifies the high frequency oscillations fed to it by the oscillator-buffer apparatus 26 and is modulated by the modulated tube 27 to which is connected the microphone 28. This circuit arrangement, that is, the circuit of the radio transmitter is conventional and well known in the art and is illustrated here only for the purpose of showing an application of my modulation indicator and the method of operation thereof. The transmitter in this case is housed in the metal cabinet 29 to which the cap 17 is connected by the wire 30.

The inside of the tube 10 is coated with particles forming the screens 18 and 19 of fluorescent material. Various substances, such as, willemite (zinc orthosilicate), zinc sulfide, zinc-cadmium sulfide, zinc silicate, calcium tungstate, and the like or combinations thereof may be employed as the luminescent screen material. These materials possess the property of fluorescence when they are subjected to electric bombardment and phosphorescence immediately thereafter. In the present invention I employ a screen 18 made up of one type of luminescent material, for example, willemite or the like. This screen 18 is substantially continuous along the inner walls of the glass tube 10 from the adjacent electrode 11 to the line 20 marked on the outside of the glass tube.

The line 20 is designated as the "100% modulation point." Adjacent to the electrode 11 may be provided a line 21 which is designated as the "no modulation point." The screen 18 extends from the line 20 to the end of the tube underneath the cap 17 and this screen is made up of different luminescent material from that out of which the screen 19 is made. The purpose for this is to obtain a clear indication when modulation in excess of 100% is produced in the signal of the radio transmitter. For example when modulation up to 100% is produced only the screen 18 will be excited and caused to become luminescent by electric bombardment. When, however modulation in excess of 100% is affected in the radio signal portions of the screen 18 will be excited. In order to produce a better indication of excessive modulation it may be desirable to make the screen 19 of material which is phosphorescent as well as fluorescent so that it remains luminescent for a period after excitation thereof. In this way the modulation peaks are more clearly indicated.

The tube 10 is thus calibrated so that the line 20 indicates the 100% modulation point and the line 21 indicates the no modulation point. Once the tube is thus calibrated the indications obtained therefrom may be duplicated and the operation of the tube is reliable and uniform. In order to insure this a small globule of mercury 31 is placed into the tube. The amount of mercury should preferably be very small although the quantity used is not critical.

In operation the tube is connected to the tank coil 23 of the transmitter through an adjustable connection or clip 22a and the variable condenser is adjusted so that the screen 18 will become fluorescent up to the line 21 when the transmitting set is not being modulated. In the circuit diagram I have illustrated the connection 22a close to the high potential end of the inductance 23 and it is of course obvious that this connection may be moved toward the lower potential end of this inductance if the indication in the tube can not be brought down to the line 21 by adjusting the condenser 16. The antenna coupling coil which is shown coupled to the lower end of the inductance 23 also may be shifted towards the high potential end if desired. However the adjustments of the antenna coil and the other circuits of the transmitter are well known in the art of radio transmission and will not be discussed in detail in this specification except insofar as they relate to this invention.

Where desired the tube 10 and condenser 16 with the associated connections may be built into the radio transmitter and a suitable slot cut into the front panel of the transmitter to enable the operator to view the tube 10 from the front of said panel. In this case only the portion between the lines 20 and 21 and a small section above and below these lines need be visible through the aforesaid slot so that the indicator may be adjusted to indicate no modulation operation of the transmitter and 100% or more modulation.

In cases where the tube 10 is not mounted inside the transmitter it is desirable to hide the electrode 11 from view and this is accomplished by placing a coating of non-conductive paint, lacquer or similar material 32 around the end of the tube. However this is not essential to the operation of the device.

Slightly modified forms of the tube 10 adapted to be used in conjunction with low frequency am-

plifiers are illustrated in Figs. 4 and 5. The tubes illustrated in these figures each employ an elongated electrode 11c extending substantially throughout the length of the tube. Auxiliary electrodes 11a and 11b are also employed in the tube shown in Fig. 4 and in this case the electrode 11b is connected to the positive terminal of the amplifier anode current supply. The electrode 11a is connected to the metal chassis or frame of the amplifier and to a terminal of the secondary 35 of the output transformer 36 connected to the amplifier. The other terminal of the secondary 35 is connected to the electrode 11c. In this form of the tube 10 an electric discharge is normally maintained between the electrodes 11a and 11b inasmuch as the electrode 11b is connected to the positive terminal of the power supply and the electrode 11a is connected to the amplifier chassis which is usually connected to a negative terminal of the same power supply. The secondary 35 impresses an alternating potential across the electrodes 11a and 11c. This alternating potential corresponds to the speech, music or other frequencies impressed upon the input of the amplifier to which the transformer 36 is connected. In cases where the amplifier characteristics are such as to amplify the speech, music or other frequencies logarithmically the tube 10, excited from the output of such an amplifier, must be made extremely long. However the necessity for making this tube of unusual length may be eliminated by adjusting the characteristics of the amplifier so that the voltage amplification thereof bears a linear relation to the amplitude of the speech, music or other frequencies impressed on the input of the amplifier.

The tube 10 shown in Figs. 4 and 5 is provided with three fluorescent screen sections 18, 19 and 19a and each of these screen sections is made up of different fluorescent material so that different sound amplitudes impressed upon the input of the amplifier may be more readily indicated. Sounds of low amplitude are indicated by fluorescence of the screen 18; sounds of intermediate amplitude are indicated by the fluorescence of the screen 19 and likewise sounds of higher amplitude are indicated by the fluorescence of the screen 19a. It is of course obvious that any amplitude calibration desired may be placed on these screens and more than three screens of distinct characteristics may be employed.

The form of the tube 10 shown in Fig. 5 also employs the elongated electrode 11c which is connected to the secondary 35 of the output transformer 36. The windings 35 and 37 of this transformer are connected together and this common connection is connected to the positive terminal of the amplifier power supply so that the primary 37 is between the power supply and the anode of an amplifier tube and the secondary 35 is connected between the tube 10 and the power supply. The auxiliary electrode 11a in this case is connected to the chassis of the amplifier. An electric discharge is maintained between this electrode and the bottom portion of the electrode 11c inasmuch as a direct current potential, supplied by the amplifier power supply, is impressed across these two electrodes. When an alternating potential which may correspond to the speech, music or other frequencies is impressed across the electrodes 11a and 11c through the operation of the transformer secondary 35, different portions of the screens 18, 19, 19a which are adjacent to the electrode 11c, will be energized and become luminescent depending upon

the amplitude of the potential impressed on the tube from the secondary 35.

This form of the tube 10 has numerous applications, one of the principal uses being in the nature of a monitor for speakers or singers speaking or singing into a radio broadcasting station microphone. By observing the fluorescence of the various screens of the tube 10 the speaker or singer will know at all times whether or not he is speaking or singing too loud into the microphone and may move to or away from the microphone so as to deliver the proper sound intensities thereto.

It is obvious that the indicator of my invention may be made in different forms without departing from the spirit or scope of this invention and therefore I do not desire to limit this device to the exact details described and illustrated except insofar as those details may be defined by the claims.

I claim:

1. Indicating apparatus for indicating the amplitude of modulations of electrical oscillations particularly when said amplitude may be excessive, comprising: an elongated tube having substantially greater length than breadth, electrode means positioned in one end of said tube, means for impressing electrical oscillations on said electrodes for producing the desired indications, a screen of fluorescent material covering substantially the entire length of the inner wall of said tube so as to be seen from the outside thereof, different sections of said screen being of fluorescent material having different color characteristics when energized, a rarified atmosphere and material in said tube to excite ultra violet light therein to energize the different sections of said screen depending upon the amplitude of the modulated electrical oscillations impressed upon said electrode means.

2. Indicating apparatus for indicating the amplitude of modulations of electrical oscillations particularly when said amplitude may be excessive, comprising: a modulated radio transmitter having a tank circuit, an elongated tube having substantially greater length than breadth, electrode means positioned in one end of said tube, connections to said tank circuit including a variable condenser for impressing electrical oscillations on said electrodes from said modulated transmitter for producing the desired indications, a screen of fluorescent material covering substantially the entire length of the inner wall of said tube so as to be seen from the outside thereof, different sections of said screen being of fluorescent material having different color characteristics when energized so that the amplitude of the modulations may be determined by observing the sections of said tube, a rarified atmosphere and material in said tube to excite ultra violet light therein to energize the different sections of said screen depending upon the amplitude of the modulated electrical oscillations impressed upon said electrode means.

3. Indicating apparatus for indicating the amplitude of modulations of electrical oscillations particularly when said amplitude may be excessive, comprising: an amplifier, an elongated tube having substantially greater length than breadth, a plurality of electrodes positioned in one end of said tube, connections for connecting said electrodes to the output of said amplifier for impressing electrical oscillations on said electrodes for producing the desired indications, a screen of fluorescent material covering substan-

- 5 tially the entire length of the inner wall of said tube so as to be seen from the outside thereof, different sections of said screen being of fluorescent material having different color characteristics when energized so that the amplitude of the modulations may be determined by observing the sections of said tube, a rarified atmosphere and material in said tube to excite ultra violet light therein to energize the different 10 sections of said screen depending upon the amplitude of the modulated electrical oscillations impressed upon said electrode means.
- 15 4. Indicating apparatus for indicating the amplitude of modulations of electrical oscillations particularly when said amplitude may be excessive, comprising: an amplifier, an elongated tube having substantially greater length than breadth, a plurality of electrodes positioned in

one end of said tube, one of said electrodes being elongated and substantially co-extensive with the interior of said tube, connections for impressing a relatively high potential on said elongated electrode from said amplifier output with respect to the other of said electrodes for producing the desired indications, a screen of fluorescent material covering substantially the entire length of the inner wall of said tube so as to be seen from the outside thereof, different sections of said 10 screen being of fluorescent material having different color characteristics when energized, a rarified atmosphere and material in said tube to excite ultra violet light therein to energize the different sections of said screen depending upon 15 the amplitude of the modulated electrical oscillations impressed upon said electrode means.

LESTER B. HOLMES.
